R. B. BENJAMIN

WATER GAUGE LIGHTING FIXTURE

Filed Aug. 7, 1918

Fig. 3.

Inventor:
Rober B. Benjamin
By: Jones, Addington, Cunes & Leibold
Attys.

UNITED STATES PATENT OFFICE.

REUBEN B. BENJAMIN, OF CHICAGO, ILLINOIS, ASSIGNOR TO BENJAMIN ELECTRIC MANUFACTURING COMPANY, OF CHICAGO, ILLINOIS, A CORPORATION OF ILLINOIS.

WATER-GAUGE LIGHTING FIXTURE.

Application filed August 7, 1918. Serial No. 243,635.

To all whom it may concern:

Be it known that I, REUBEN B. BENJAMIN, a citizen of the United States, residing at Chicago, in the county of Cook and 5 State of Illinois, have invented new and useful Improvements in Water-Gauge Lighting Fixtures, of which the following is a full, clear, concise, and exact description, reference being had to the accompanying drawing, forming a part of this specification.

This invention relates to improvements in water gauge lighting fixtures and relates particularly to a fixture designed to be used in connection with the water level gauge 15 on a steam boiler for the purpose of lighting the water tube, means being provided for screening the light except that which falls directly upon this tube.

One of the objects of the invention is to 20 provide a device of this type which is economical to manufacture and of simple construction. Another object is to provide a fixture of this type which is so constructed that the lamp may be readily removed for 25 cleaning or replacement.

In the accompanying drawings, in which I have illustrated a fixture embodying my invention;

Figure 1 is an elevational side view of a 30 steam gauge fitted with one of these fixtures;

Fig. 2 is an elevational front view of the fixture, shown partly in section, and

Fig. 3 is a top plan view of the lower part of the fixture as seen from a plane indicated 35 by the line 3-3 on Fig. 1.

In the several figures of the drawings, in which like reference numerals indicate the same parts throughout, 10 represents a boiler of a steam generating plant. Short tubes 40 11 and 12 connect the water glass 13 at its ends to the boiler and establish communication between the tube and the same. The upper portion of the fixture comprises a hollow fitting 15, which is adapted to be 45 clamped upon the tube 11, this fitting being formed with a notch or slot in its upper surface for the reception of the tube 11 and being provided with a clamping plate 16, which extends over the tube 11 and is drawn 50 down against fitting 15 by a pair of screws 17 and 18. This fitting 15 has a nipple or neck 19 upon its lower portion, this neck being screw threaded to receive the internally threaded neck 20 of a lamp receptacle 55 or socket 21. The fitting 15 is formed with

a screw-threaded side opening 22 for the reception of the threaded end of a conduit pipe 23. The conductors which supply current for the lamp are led in through the conduit pipe 22 and extend down through 60 the hollow neck 19 into the socket 21, where they are attached to the binder terminals of the latter.

The shield 24 which confines the light and prevents its passing from the lamp in any 65 direction except directly toward the water glass 13, consists of a piece of sheet metal, bent into cylindrical form, and left with its vertical edges separated by a distance slightly greater than will be required when the 70 article is assembled. This member 24 is clamped upon the receptacle 21 by means of a ring 25, the latter consisting of a strip of sheet metal, curved so that its ends nearly meet, these ends being turned outward and 75 provided with openings through which is passed a small bolt 26 provided with a nut 27. When the bolt is tightened the ends of the ring 25 are drawn together, so as to clamp the sheet metal shield 24 into firm 80 engagement with the casing shell of the receptacle 21. These shells are usually made with a bead 28 on the lower edge of the shell. To cooperate with this bead, there is formed on the shield 24 a similar bead 29, into which 85 fits the bead 28 on the receptacle shell. When the clamping screw is tightened and the clamping ring 25 is drawn down upon the member 24, the latter is prevented from moving up or down by the interlocking of 90 these beads. The upper edge of the shield 24 is flanged outward at 24^a, the clamping ring 25 being confined between this flange and the bead 29.

The lower end of the member 24 is also 95 formed with a bead 30. The lower end of the fixture consists of a hemispherical bowl-shaped member 31 having a bead 32 to receive the bead 30 of the shield. When the device is assembled the vertical edges of the 100 shield are separated by a space just sufficient to permit the lamp to properly illuminate the water tube of the gauge. The tendency of the shield to open holds the cap in position as long as the bead on the shield is engaged in the bead on the cap. To remove the lamp the shield 24 is compressed to bring the vertical edges 33 and 34 closer together and permit the cap to be drawn off over the bead. 105

It will be seen that this device is of extremely simple construction and economical to manufacture and does not require complicated tools, dies or the like.

5 Having thus described my invention, what I claim as new and desire to secure by Letters Patent is:

1. In a device of the class described, the combination of a fitting arranged to be secured to a water level gauge and having a threaded neck for the reception of a lamp holding device, a shield comprising a strip of sheet metal rolled into cylindrical form and having its edges separated to permit the 10 passage of light to the tube of the gauge, a removable cap for one end of said sheet metal member, and means for clamping said shield to the lamp holding device.

2. A device of the class described, comprising a fitting arranged to be clamped to a water gauge, said fitting having an inlet for feed wires and arranged to support a lamp holding receptacle, a light-confining shield comprising a strip of sheet metal rolled into cylindrical form and having its edges separated, means for clamping the upper edge of said shield to the lamp holding receptacle, and a cap for the opposite end of said shield, said cap being arranged to be held in position by the tendency of the sheet metal shield to open.

3. A lighting fixture for water gauges comprising a strip of sheet metal formed into a tube and having its edges separated 30 forming a longitudinal opening, means for securing said member at one of its ends to a lamp holding receptacle, whereby said end is closed by said receptacle, and means for

closing the opposite end of said member, said means embracing said end and being held in position by the tendency of the sheet metal strip to open.

4. A lighting fixture for water gauges, comprising a lamp holding device, means for supporting the lamp holding device, a light-confining shield comprising a strip of sheet material bent into cylindrical form and having its edges separated to permit the passage of light therebetween, one end of said member having a bead formed thereon, a cap 40 arranged to snap upon said member and having a bead for co-operation with the bead of the latter, said cap being held in position by the tendency of the cylindrical member to expand in the cap, and means for clamping the opposite end of said cylindrical member to the lamp holding device.

5. The combination with a water gauge and a boiler to which the same is applied, of a fitting interposed between said gauge and boiler for illuminating said gauge, said fitting comprising a lamp and a receptacle for the same, a tubular shield rolled from a sheet whereby it may be fitted around said lamp and clamped into place around said receptacle to leave a light slit that is parallel to said gauge to illuminate the latter, means for securing said tubular member at one end to the outside of said receptacle, a cap member to fit over the other end of said tubular member and be held in place thereover by the tendency of the metal tube to open.

In witness whereof, I have hereunto subscribed my name.

REUBEN B. BENJAMIN.
